US00D632843S

(12) **United States Design Patent**
Wilson et al.

(10) **Patent No.:** US D632,843 S
(45) **Date of Patent:** ** Feb. 15, 2011

(54) **LAVATORY CLEANSING BLOCK**

(75) Inventors: **Brian Wilson**, Norfolk (GB); **David Stuart**, Glasgow (GB)

(73) Assignee: **Jeyes Group Limited** (GB)

(**) Term: **14 Years**

(21) Appl. No.: **29/272,605**

(22) Filed: **Feb. 12, 2007**

(51) **LOC (9) Cl.** **28-02**

(52) **U.S. Cl.** **D28/8.1**

(58) **Field of Classification Search** D28/4, D28/8.1, 8.2, 99; D24/100–103; D23/207–208, D23/200, 295, 303, 309, 499; 510/440–442, 510/445–450, 221, 224, 225, 141, 143, 147, 510/294, 439, 298
